UNITED STATES PATENT OFFICE.

ELBERON D. SMITH, OF BROOKLYN, NEW YORK, ASSIGNOR TO AMERICAN MACHINE & FOUNDRY COMPANY, OF NEW YORK, N. Y., A CORPORATION OF NEW JERSEY.

CIGARETTE-ROD-FORMING MECHANISM.

1,075,272.

Specification of Letters Patent. Patented Oct. 7, 1913.

Application filed October 4, 1912. Serial No. 723,830.

To all whom it may concern:

Be it known that I, ELBERON D. SMITH, a citizen of the United States, residing at Brooklyn, county of Kings, and State of New York, have invented a new and useful improvement in Cigarette-Rod-Forming Mechanisms, of which the following is a specification.

This invention relates to an improvement in cigarette rod forming mechanisms, particularly adapted for use in connection with high speed cigarette machines of the continuous rod type.

Heretofore in machines of this type it has been customary to shower shredded tobacco into a trough, the bottom of which is formed by a moving belt and the side walls of which in some instances are also formed of moving belts. In such machines the tobacco is pushed across a bridge at the end of the trough onto a moving strip of wrapping paper supported by a second moving belt which runs through a rod forming tube, the particular function of which is to curl the wrapping paper up around the tobacco lying thereupon and to compress the tobacco into a closed continuous rod. In ordinary cigarette machines of the old well-known type, the traveling belts forming the bottom and side walls of the trough were the cause of considerable trouble in the operation of the machine. One reason for this trouble was the excessive wear due to the constant grinding of the belts which was caused by the gritty substances in the tobacco itself. Another cause was the difficulty in evenly transferring the tobacco from the trough across the bridge into the rod forming tube. In high speed machines these difficulties are more pronounced than in the old well-known machines, for obvious reasons.

The main object of the present invention is the production of a cigarette rod forming machine which is entirely free from the defects of the old traveling trough mechanisms.

A further object is the production of a device in which the serious defects of the older machines are eliminated and in which the tobacco is showered directly upon the strip of wrapping paper in which it is to be afterward inclosed.

Still another object is the production of a device of the general character above mentioned in which the paper is led over a

straight runway where it receives the shower of tobacco and is then, at a position beyond and in alignment with the runway, curled up around the tobacco and sealed to form a closed continuous rod.

With these and other objects not specifically mentioned in view, the invention consists in certain constructions and combinations which will be hereinafter fully described and then specifically set forth in the claims hereunto appended.

In the accompanying drawings which form a part of this specification and in which like characters of reference indicate the same or like parts, Figure 1 is a plan view of one end of a device constructed in accordance with the invention; Fig. 2 is a side elevation of the structure shown in Fig. 1; Figs. 3 and 4 are respectively extensions of the structures shown in Figs. 1 and 2; Fig. 5 is a sectional view taken on the line 5 in Fig. 1 and enlarged; and Fig. 6 is an enlarged perspective view of the tobacco receiving trough and sectioned at the line 6 in Fig. 1.

In carrying the invention into effect, there is provided a runway along which a strip of wrapping paper is drawn, said runway being adapted to guide a shower of tobacco directly upon the wrapping paper within which it is to be afterward inclosed. There is further provided means for compacting the tobacco on and inclosing it within the wrapping paper to form a closed continuous rod. In the best constructions, a straight runway will be employed which coöperates with means beyond and in alignment therewith for compacting the tobacco and inclosing it within the wrapping paper to form a closed continuous rod. This runway and inclosing means may vary in construction within wide limits.

It is to be understood that the device selected to illustrate the invention is but one of many possible constructions lying within the invention. In this device, 1 indicates a cigarette machine bed of a type used in high speed continuous rod cigarette machines. Mounted upon one end of this bed is a bracket 2, the cross-section of which is in the form of a reversed angle, the upper surface of the bracket lying above and in front of the bed 1. This bracket may be secured to the bed by any suitable means well known to mechanics.

The bracket 2 supports two pairs of integral transversely extending arms 3, 3 and 4, 4. Each arm 3 is connected with the adjacent arm 4 by means of a pintle 5. Mounted to slide and rotate upon these pintles are arms 6. Two of these arms are integrally connected with a casting 7 which extends along the greater part of the length of the bracket 2 and forms the front side wall of a trough of which the operating face of the bracket 2 is the bottom. Similarly, the other two arms 6, 6 are integrally connected with a similar casting 8, forming the rear side wall of the trough before referred to. The function of this trough is to guide a shower of tobacco upon a strip of wrapping paper running along the upper operating face of the bracket 2 between the side walls 7 and 8 and otherwise unsupported, the operating face of the bracket forming a runway for the paper. For the purpose of guiding the strip of wrapping paper running through the runway against lateral displacement, the adjacent lower edges of the castings 7 and 8 are rabbeted respectively at 9 and 10 so that the extreme edges of the strip of paper run under the upstanding portions of the castings 7 and 8 and do not receive tobacco and are left clear so that they may later be folded around the tobacco and seamed. At the extreme end of the bracket 2 is a smaller bracket 11 carrying a roller 12 over which the paper is led through the runway, it being understood that the paper comes from a reel suitably mounted in the machine in a well-known manner. The castings 7 and 8 are swingable upon the pintles 5 and are also capable of longitudinal movement thereon. The purpose of this construction is to enable the operator of the machine to swing them out of the way, thus exposing the entire upper surface of the bracket 2 for cleaning or other purposes. While the machine is in operation, however, the castings 7 and 8 are securely locked in operative position. This result is effected in the following manner. Each of the arms 6 is provided with a notch 13 and between each of the arms 6 and the adjacent arm 4 there is located a collar 14 having a lug or projection 15 adapted to engage the notch 13 before referred to. Each of the collars 14 is loosely mounted upon the pintles 5 and each has a dependent lug 16 through which is threaded a screw 17 bearing against the bracket 2. To lock the castings in operative position, they are swung down into contact with the operating surface of the bracket 2 and moved longitudinally upon their respective pintles until the notch 13 engages the projection 15 of the operating collars 14. The screws 17 are then operated to cause a slight rotary movement of the collars 14 and projections 15, which results in firmly holding the castings

in operative position. The castings 7 and 8 are released by a reverse movement of the screws 17. In Fig. 2 there is illustrated diagrammatically the lower end of a hopper 18 of well-known construction and operated in a well-known manner and which cooperates with the trough to guide a falling shower of tobacco into said trough.

At a point adjacent the delivery end of the trough is a presser wheel 19 which is mounted upon a shaft 20 journaled in bearings 21, 22 formed on a bracket 23. The bracket 23 is provided with two rearwardly extending bosses 24, 25, which bosses are journaled upon a sleeve 26 (see Fig. 5). This sleeve 26 is held in position within a support 27 by means of a set screw 28. The support 27 is formed integrally on a bracket 28' which carries two other supports 29, 30, the axes of which are in alignment with the axis of the support 27. Within the supports 29, 30 and also within the sleeve 26 is journaled a shaft 31. Pinned to this shaft is a gear 32 in mesh with a similar gear 33 fast upon the shaft 20 before referred to. A spiral gear 34 is also secured to the shaft 31 and this spiral gear is in mesh with a second gear 35 fast upon a shaft 36 extending downward through a long bearing 37 and carrying upon its lower end a beveled gear 38, which beveled gear is in constant mesh with a bevel pinion 39 fast upon and rotated by a shaft 40, which shaft is or may be one of the main power shafts of the machine. The peripheral speed of the presser wheel 19 is approximately equal to the speed of the strip of wrapping paper and the tobacco carried thereby which passes under the presser wheel. The presser wheel compacts the tobacco to a predetermined extent which may be varied by adjusting the bracket 23 to vary the relative vertical positions of the trough and presser wheel. This adjustment is effected by means of a set screw 41 threaded in the bracket 28' and bearing against the bracket 23 to the right of the shaft 31 (see Fig. 1).

Beyond the extreme left end of the trough is a bridge 42 over which the paper carrying the tobacco runs. This bridge is supported by a bracket 43 suitably supported by the bed of the machine. The bracket may be adjusted laterally in an obvious manner by means of the set screw 44 and held in adjusted position by means of the thumb-screw 45. After the paper carrying the tobacco has passed over the bridge 42, it enters the rod forming mechanism proper which operates to fold the wrapping paper around the tobacco and seal the same to form a closed continuous rod. This rod forming mechanism includes a rod forming tube generally indicated by the numeral 46 and constructed and operated in a well-known manner. Since the specific construc-

- tion of this rod forming tube lies beyond the present invention and is well known in the art, a specific description thereof is omitted. It may be remarked, however, that 5 coöperating with the tube is an endless belt 47 driven by a pulley 48 and passing over a gripping wheel 49 and adjusting rollers 50 and through a suitable guiding mechanism 51 and over a suitable guiding roller 52 located at the entrance of the rod forming tube and under the bridge 42 before referred to. The pulley 48 derives its motion from a shaft upon which it is mounted. This shaft is journaled in a suitable bearing 53 10 carried by the bed 1. Upon its rear end is mounted a worm wheel 54 which is in mesh with a worm 55, which worm is fast upon and driven by the power shaft 40 before referred to.
- 20 A pasting wheel forming a part of a pasting mechanism for securing the edges of the wrapping paper together is indicated by the broken circle at 56, and a seaming belt the function of which is to press the 25 pasted seam together to cause the pasted edges to adhere firmly is indicated at 57 by the broken circles and lines. The particular construction of the pasting mechanism and seaming device lies wholly beyond 30 the range of the present invention, and a detailed description thereof is therefore omitted. By an inspection of the drawings, it will be readily understood that the runway for the wrapping paper is a straight runway and that the rod forming mechanism proper lies beyond said runway and in alignment therewith. It will be readily understood also that the tobacco is not disturbed after it is originally showered upon the 40 moving paper in the trough formed by the bracket 2 and the castings 7 and 8, except to be compacted and formed into the shape of the finished cigarette rod. In other words, it is not advanced by one means and 45 transferred to a second advancing means, as is the case in the machines well known in the art; but it is showered directly upon the paper in which it is afterward inclosed.
- In view of the foregoing, a detailed description of the operation of the device is 50 deemed unnecessary to a full understanding of the invention and such description is therefore omitted.
- What is claimed is:
- 55 1. In a cigarette rod forming mechanism, the combination with a trough having side walls and a stationary bottom and adapted to form a runway for a strip of wrapping paper otherwise unsupported and also adapted to receive a shower of tobacco on and above the wrapping paper, of means beyond 60 and coöperating with the trough for forming the wrapping paper and the tobacco thereupon into a continuous rod.
- 65 2. In a cigarette rod forming mechanism,
- the combination with a trough having rabbeted side walls and a stationary bottom and adapted to form a runway for a strip of wrapping paper otherwise unsupported and guided by the wall rabbets and also 70 adapted to receive a shower of tobacco on and above the wrapping paper, of means beyond and coöperating with the trough for forming the wrapping paper and the tobacco thereupon into a continuous rod. 75
3. In a cigarette rod forming mechanism, the combination with a trough having hinged side walls and a stationary bottom and adapted to form a runway for a strip of wrapping paper otherwise unsupported 80 and also adapted to receive a shower of tobacco on and above the wrapping paper, of means for locking the side walls in operative position, and means beyond and coöperating with the trough for forming the wrapping paper and the tobacco 85 thereupon into a continuous rod.
4. In a cigarette rod forming mechanism, the combination with a trough having hinged and rabbeted side walls and a stationary bottom and adapted to form a runway for a strip of wrapping paper otherwise unsupported and also adapted to receive a shower of tobacco on and above the wrapping paper, of means for locking the 90 side walls in operative position, and means beyond and coöperating with the trough for forming the wrapping paper and the tobacco 95 thereupon into a continuous rod.
5. In a cigarette rod forming mechanism, the combination with a trough having a pair 100 of side walls and a stationary bottom and adapted to form a runway for a strip of wrapping paper otherwise unsupported and also adapted to receive a shower of tobacco on and above the wrapping paper, each of 105 said side walls having a pair of transversely extending arms, pintles upon which the wall arms are slideable and rotatable, means for locking the side walls in operative position, and means beyond and coöperating with the trough for forming the wrapping paper and the tobacco 110 thereupon into a continuous rod.
6. In a cigarette rod forming mechanism, the combination with a trough having a pair 115 of side walls and a stationary bottom and adapted to form a runway for a strip of wrapping paper otherwise unsupported and also adapted to receive a shower of tobacco on and above the wrapping paper, each of 120 said side walls having transversely extending arms each provided with a notch, pintles upon which said arms are slideable and rotatable, locking devices provided with projections adapted to engage the notches of the 125 side wall arms and adapted to lock said side walls in operative position, and means beyond and coöperating with the trough for forming the wrapping paper and the tobacco thereupon into a continuous rod. 130

7. In a cigarette rod forming mechanism, the combination with a trough having a pair of side walls and a stationary bottom and adapted to form a runway for a strip of wrapping paper otherwise unsupported and also adapted to receive a shower of tobacco on and above the wrapping paper, each of said side walls having transversely extending arms each provided with a notch, pintles upon which said arms are slideable and rotatable, screw actuated locking devices provided with projections adapted to engage the notches of the side wall arms and adapted to lock said side walls in operative position, and means beyond and coöperating with the trough for forming the wrapping paper and the tobacco thereupon into a continuous rod. 60
8. In a cigarette rod forming mechanism, the combination with a trough having side walls and a stationary bottom and adapted to form a runway for a strip of wrapping paper otherwise unsupported and also adapted to receive a shower of tobacco on and above the wrapping paper, of a forming tube located beyond and in alinement with the trough, a belt running in said tube and adapted to close the wrapping paper around the tube advanced thereby, and means for 70 seaming the edges of the wrapping paper to form a closed continuous rod. 75
9. In a cigarette rod forming mechanism, the combination with a trough having side walls and a stationary bottom and adapted to form a runway for a strip of wrapping paper otherwise unsupported and also adapted to receive a shower of tobacco on and above the wrapping paper, of a forming tube located beyond and in alinement with the trough, a belt running in said tube and adapted to close the wrapping paper around the tobacco advanced thereby, and means including a pasting device for seaming the edges of the wrapping paper together to 80 form a closed continuous rod. 85
10. In a cigarette rod forming mechanism, the combination with a trough having side walls and a stationary bottom and adapted to form a runway for a strip of wrapping paper otherwise unsupported and also adapted to receive a shower of tobacco on and above the wrapping paper, of a forming tube located beyond and in alinement with the trough, a belt running in said tube and adapted to close the wrapping paper around the tobacco advanced thereby, and means including a pasting device and a seam pressing device for seaming the edges of the wrap- 90
- ping paper together to form a closed continuous rod. 95
11. In a cigarette rod forming mechanism, the combination with a trough having side walls and a stationary bottom and adapted to form a runway for a strip of wrapping paper otherwise unsupported and also adapted to receive a shower of tobacco on and above the wrapping paper, of a pressing device coöperating with the trough at its delivery end to compact the tobacco on and above the wrapping paper, a forming tube located beyond and in alinement with the trough, a belt running in said tube and adapted to close the wrapping paper around the tobacco advanced thereby, and means including a pasting device and a seam pressing device for seaming the edges of the wrapping paper together to form a closed continuous rod. 100
12. In a cigarette rod forming mechanism, the combination with a stationary trough-like runway along which a strip of wrapping paper is drawn said runway being adapted to guide a shower of tobacco directly upon the wrapping paper, and means for compacting the tobacco on and inclosing it within the wrapping paper to form a closed continuous rod. 105
13. In a cigarette rod forming mechanism, the combination with a straight stationary trough-like runway along which a strip of wrapping paper is drawn said runway being adapted to guide a shower of tobacco upon the wrapping paper, and means beyond and in alinement with the runway for compacting the tobacco and inclosing it within the wrapping paper to form a closed continuous rod. 110
14. In a cigarette rod forming mechanism, the combination with a straight stationary trough-like runway along which a strip of wrapping paper is drawn said runway being adapted to guide a shower of tobacco upon the wrapping paper, and means including a forming tube and a belt operating beyond and in alinement with the runway for compacting the tobacco and inclosing it within the wrapping paper to form a closed continuous rod. 115

In testimony whereof, I have signed my name to this specification in the presence of two subscribing witnesses.
